CLOTHES WASHING DEVICE

Filed April 15, 1927

Inventor
August Hormel
By his Attorney
Thompson

UNITED STATES PATENT OFFICE

AUGUST HORMEL, OF HUDSON HEIGHTS, NEW JERSEY

CLOTHES-WASHING DEVICE

Application filed April 15, 1927. Serial No. 183,957.

My invention relates to improvements in laundry appliances, and more particularly has reference to means adapted for washing and wringing clothes.

5 In the accompanying drawing, I have illustrated an embodiment of my invention as applied to a portable arrangement of automatic washboard and wringer, adapted to be positioned adjacent the side of a washtub.

10 Referring to said drawing, 1 indicates a tubular standard suitably secured in a base 2, having a telescopic upper portion 3, which may be vertically adjusted therein by any suitable means such as the thumb screws 4.

15 5 indicates a bracket which may be rotatably secured upon the upper portion 3, by any suitable means such as the hand wheel 6, said bracket having an upwardly projecting portion 7, to which may be secured the clothes

20 wringer 8, said wringer having a drive shaft 9, upon which is secured a large pinion 10, and small sprocket 11, within the housing 12, the large pinion meshing with a smaller pinion upon the shaft 13, of the motor 14, and

25 the small sprocket 11 being connected by sprocket chain 15 to the sprocket 16, upon the shaft 17, which also carries a beveled pinion 18, which meshes with beveled pinion 19, upon the shaft 20, which carries beveled pinion 21, meshing with beveled pinion 22, upon the shaft 23, mounted in the plate 30 provided with brackets 25, hinged upon the shaft 17, as shown, 26 indicating depending lugs or arms providing bearings for said shaft 17, the

30 same being also suitably secured to the wringer 8 by bolts or screws 27, or other suitable means.

28 indicates a washboard of circular form, mounted at the center upon the shaft 23, so 40 as to be rotated by the motor 14, and is provided with radial or tangential corrugations 29, against which the clothes are pressed or rubbed while the same rotates within the tub.

45 In the position shown in the drawing, the washboard is shown substantially horizontal for purpose of clearness, but it will be observed that a segmental plate 30 is provided with a curved slot 31, through which the wing-screw 32 passes, entering a threaded

50 hole in the hinged support 24, so that the

board may be turned upon the axis or shaft 20 to the desired angle convenient for rubbing the clothes thereupon, in other words, the front portion is of course raised, allowing the circular washboard to extend into the water in the tub.

32 indicates an upper portion suitable for carrying the soap or other articles, and the driving mechanism is of course preferably housed as indicated at 33, 34. 35 indicates wing-screws adapted to pass through the depending lugs 36 of the base portion 26, to bind the wall 37 of the tub in said base portion, as shown, thereby giving additional security and rigidity to the appliance when placed in position adjacent the tub for use.

For purposes of illustration, a conventional form of wringer has been shown, and likewise a rotatable washboard, but of course it will be understood that the ordinary form of washboard may be secured upon a bearing such as 20 and operate in substantially the same manner as an automatic washboard, so that when out of use either form of washboard may be folded up substantially flat and parallel with the wringer upon the axis 17. It will also be readily appreciated that the stand may be omitted, and the whole appliance may be secured by suitable means such as wing-screws 35 to the tub 37, or the stand alone may be employed without attaching means for the tub. It will also be readily understood that the motor 14 may be secured at the other end of the wringer 8, or upon the top of the same or in any other convenient position, and that the transmission parts may also be placed at the other side if desirable, thus affording complete clearance at the front of the tub, in fact, various modifications may be made in the construction and arrangement of parts without departing from the spirit of the invention as claimed.

I claim:

1. A device of the class described, including a standard with means thereon to support a washboard rotatable about one axis, and other means to support the board for rotation about an axis at right angles to the first named axis.

2. A device of the class described, includ-

100

ing a standard with means thereon to support a washboard rotatable about one axis, and other means to support the board for rotation about an axis at right angles to the first named axis, and in combination therewith a motor on said standard with driving connections to said washboard, said connections being co-axial with the axes of rotation of said board.

10 In testimony whereof I hereunto affix my signature.

AUGUST HORMEL.
